FIVE-ROLL DOUBLE-DRAFT FRAME

James D. Friday and William F. Stilwell, Dallas,
N. C., assignors of one-half to Forney D. Mays
and Emery L. Williams, Dallas, N. C., jointly

Application November 18, 1949, Serial No. 128,094

4 Claims. (Cl. 19—130)

1

This invention relates to spinning frames, and more particularly to a spinning frame for spinning long draft textile fibers.

A main object of the invention is to provide a novel and improved spinning frame employed as the finishing apparatus for completing the spinning operation on yarn, said frame being very simple in construction, providing a double-draft action on the spun yarn, and being particularly applicable in spinning long-draft nylon yarn and the like.

A further object of the invention is to provide an improved double-draft spinning frame for providing the final draft in spinning textile fibers, said frame being relatively inexpensive to manufacture, being easy to install, involving only a few parts, preventing the formation of slugs or kinks in the spun yarn, and providing a practical means of long-draft spinning of nylon yarn.

Further objects and advantages of the invention will become apparent from the following description and claims, and from the accompanying drawings, wherein:

Figure 1 is a vertical transverse cross-sectional view taken through an improved long-draft, yarn-spinning machine constructed in accordance with the present invention;

Figure 2 is a fragmentary top plan view of the spinning frame of Figure 1;

Figure 3 is a fragmentary front elevational view of the spinning frame of Figure 1.

Figure 4 is a vertical transverse cross-sectional view taken on line 4—4 of Figure 3.

Referring to the drawings, 11 designates the base of the drafting machine, and 12, 13 designate respective pedestals secured to said base. Designated at 14, 15 are respective parallel inclined bracket members secured to the top ends of the pedestals 12, 13. Secured to the bracket members are respective, successively arranged sets of bearing blocks 17, 18 and 19, and pivoted at 20, 20 to the upper ends of the bearing blocks 19, 19 is a frame 16 formed with side arms 21, 21 and with an intermediate arm 22. Journaled between the respective side arms 21, 21 and the intermediate arm 22 are the respective sets of shafts 23, 24, 25 and 26, each shaft carrying spaced pressure rollers shown at 27, 28, 29 and 30.

Journaled in the end portions of the bracket members 14, 15 below the rollers 30 is a longitudinal shaft 31 formed with fluted roller portions 32 which are disposed subadjacent the respective rollers 30. Journaled in the bearing blocks 17 is a longitudinal shaft 33 formed with fluted roller portions 34 which are disposed subadjacent

2

the respective rollers 29. Journaled in the bearing blocks 18 is a longitudinal shaft 35 formed with a continuous roller element 36. Journaled in the bearing blocks 19 below the rollers 28 is a longitudinal shaft 38 disposed subadjacent the respective rollers 28. Journaled in the bearing blocks 19 below the rollers 27 is a longitudinal shaft 39 formed with fluted roller portions 40 disposed subadjacent the respective rollers 27.

10 The right end portion of shaft 31, as viewed in Figure 2, is connected to a suitable driving means, not shown. The left end of shaft 31 is drivingly coupled to the left end of shaft 33 by a speed-reducing gear train, comprising a small gear 41 carried by shaft 31 which meshes with a large gear 42. Gear 42 carries coaxially and integrally therewith a small gear 43 which meshes with a larger gear 44 carried by shaft 33. Gear 42 is rotatably secured to a bracket bar 45 secured to an upstanding support bar 46 which, in turn, is secured to base 11.

15 The right end portion of shaft 31 is drivingly coupled to the right end portion of shaft 39, as viewed in Figure 2, by a speed-reducing gear train comprising a small gear 47 carried by shaft 31 which meshes with a large gear 48. Gear 48 carries coaxially and integrally therewith a small gear 49 which meshes with a larger gear 50 carried by shaft 39. Gear 48 is rotatably secured to a bracket bar 51 secured to an upstanding support bar 52, which in turn, is secured to base 11.

20 The right end portion of shaft 39 is drivingly coupled to the right end portion of shaft 37 by a gear train comprising a gear 53 carried by shaft 39, an idler gear 54 meshing with gear 53, and a gear 55 carried by shaft 37 which meshes with idler gear 54. Idler gear 54 is rotatably secured to a bracket bar 56 secured by a bolt 57 to the right hand bearing block 19.

25 The left end portion of shaft 37 is drivingly coupled to the left end portion of shaft 35 by a gear train comprising a gear 58 carried by shaft 37, an idler gear 59 meshing with gear 58, and a gear 60 carried by shaft 35 which meshes with idler gear 59. Idler gear 59 is rotatably secured to a bracket bar 61 secured by a bolt 62 to an upstanding support bar 63 secured to base 11.

30 It will be apparent that each of the shafts 33, 35, 37 and 39 will rotate in the same direction as the driving shaft 31, but at slower speeds than said driving shaft.

Designated at 64 is a longitudinally extending

55 cleaning roller carried on a shaft 66 rotatably

supported in bearing seats formed in the ends of respective levers 65, 65 pivoted at their intermediate portions to the respective pedestals 12 and 13, as shown at 67 in Figure 1. The inner ends of the levers 65, 65 carry enlarged weighted elements 68, biasing the levers 65 clockwise, as viewed in Figures 1 and 4. Roller 64 is disposed subadjacent the fluted rollers 32 and engages said fluted rollers with substantial pressure, whereby roller 64 is rotated by its frictional engagement with the fluted rollers, and clears the fluted rollers of loose fibers and lint.

Overlying and engaging the shafts 23, 24, 25 and 26 between the rollers carried on said shafts are respective bar members 69, each bar member 69 having connected thereto a depending slotted bar 70 which extends downwardly between the pressure rollers 29 and 30 and between the fluted rollers 32 and 34, as shown in Figure 5, and engages around a weighted lever 71 pivotally hooked beneath a pin 72 projecting from an adjacent pedestal 13. Adjustably carried on each lever 71 is a weight 73. By adjusting the positions of weights 73 on levers 71, the amount of downward pressure exerted by rollers 27, 28, 29 and 30 on the fluted rollers 40, 38, 34 and 32 may be regulated.

In operation, the partly finished roving 75 is fed from vertical bobbins 74 rotatably mounted in positions rearwardly adjacent the drafting frame, as shown in Figure 1, through the rollers 27, 40, the rollers 28, 38, over roller 36, through the rollers 29, 34 and through the relatively rapidly rotating rollers 30, 32, the finished drafted roving, shown at 76, passing through an eye member 77 and being wound on a spool 78 which is rotated by a suitable spindle. Since the fluted rollers 32 rotate more rapidly than the fluted rollers 34, 35 and 40, considerable draft is applied to the roving between the initial rollers 27, 40 and the final rollers 30, 32. The pressure exerted on the roving by the various sets of rollers allows the roving to be uniformly drawn out and simultaneously smooths the fibers thereof, preventing the formation of kinks or slugs in the yarn.

The main draft occurs between the fluted rollers 32 and the fluted rollers 34, since there is maximum difference in speed of rotation between these rollers. However, a certain amount of further draft occurs off the rollers 40 and 38. Besides providing further draft, rollers 40, 38 and 34 act as slip rolls to take out and to prevent slugs or kinks in the yarn. The intermediate smooth roller 36 acts as a support for the drafted roving between rollers 34 and 38 and allows the tension in the yarn to equalize itself between said rollers 34 and 38. The rotating spool 78 provides a slight amount of twist and final draft to the finished yarn.

The above-described drafting machine is particularly suitable for finishing fine yarns such as refining nylon roving, no previously employed machine having been found suitable for running fine nylon yarn.

While a specific embodiment of a long-draft yarn-spinning frame has been disclosed in the foregoing description, it is understood that various modifications within the spirit of the invention may occur to those skilled in the art. Therefore, it is intended that no limitations be placed on the invention except as defined by the scope of the appended claims.

What is claimed is:

1. In a spinning frame, a roving-drafting ap-

paratus of the character described, comprising a first pair of fluted rolls, a second pair of fluted rolls, a smooth roll located between said first and second pairs, all of the rolls being parallel and being coplanar, a first gear train coupling the outer roll of the second pair to the outer roll of the first pair, a second gear train coupling the outer roll of the second pair to the inner roll of the second pair, both of said gear trains being formed and arranged to drive said outer roll of the first pair and said inner roll of the second pair in the same direction but at reduced speed with respect to the outer roll of the second pair, a third gear train coupling the outer roll of the first pair to the inner roll of the first pair for simultaneous rotation in the same direction, a fourth gear train coupling the smooth roll to the inner roll of the first pair for simultaneous rotation in the same direction, respective pressure rolls overlying and engaging the respective fluted rolls, a cleaning roller disposed in subadjacency to and parallel with the first pair of fluted rolls, pivoted levers supporting said roller, said levers being mounted for movement about an axis parallel with the axes of the first pair of fluted rolls and weighted elements associated with said levers for retaining said roller in frictional engagement of the outer roll of the first pair, the rollers of each pair being spaced a distance less than the space between pairs.

2. In a spinning frame, a roving-drafting apparatus of the character described, comprising a first pair of fluted rolls, a second pair of fluted rolls, a smooth roll located between said first and second pairs, all of the rolls being parallel and being coplanar, a first gear train coupling the outer roll of the second pair to the outer roll of the first pair, a second gear train coupling the outer roll of the second pair to the inner roll of the second pair, both of said gear trains being formed and arranged to drive said outer roll of the first pair and said inner roll of the second pair in the same direction but at reduced speed with respect to the outer roll of the second pair, a third gear train coupling the outer roll of the first pair to the inner roll of the first pair for simultaneous rotation in the same direction, a fourth gear train coupling the smooth roll to the inner roll of the first pair for simultaneous rotation in the same direction, a frame pivotally overlying the fluted rolls, pressure rollers rotatably journaled in said frame, said pressure rollers being respectively vertically aligned with the fluted rolls, adjustable weight means operatively connected to said frame for retaining said pressure rollers in engagement with the fluted rolls and a cleaning roller pivotally disposed in subadjacency to and parallel with the outer roll of the first pair of fluted rolls and weighted elements associated with said cleaning roller for retaining said roller in frictional engagement of the outer roll of the first pair, the rollers of each pair being spaced a distance less than the space between pairs.

3. In a spinning frame, a roving-drafting apparatus of the character described comprising a first pair of closely spaced fluted rolls, a second pair of closely spaced fluted rolls spaced from said first pair by a distance greater than the space between the rolls of the respective pairs, a smooth roll located between said first and second pairs, all of the rolls being parallel and being coplanar, means coupling the outer roll of the second pair to the outer roll of the first pair,

means coupling the outer roll of the second pair to the inner roll of the second pair, said coupling means being formed and arranged to drive said outer roll of the first pair and said inner roll of the second pair in the same direction but at reduced speed with respect to the outer roll of the second pair, means coupling the outer roll of the first pair to the inner roll of the first pair for simultaneous rotation in the same direction, means coupling the smooth roll to the inner roll of the first pair for simultaneous rotation in the same direction, and respective pressure rolls overlying and engaging the respective fluted rolls.

4. In a spinning frame, a roving-drafting apparatus of the character described comprising a first pair of fluted rolls, a second pair of fluted rolls, said first pair of rolls being spaced from said second pair by a distance greater than the space between the rolls of the respective pairs, a smooth roll located between said first and second pairs, all of the rolls being parallel and being coplanar, a first gear train coupling the outer roll of the second pair to the outer roll of the first pair, a second gear train coupling the outer roll of the second pair to the inner roll of the

10

15

25

second pair, both of said gear trains being formed and arranged to drive said outer roll of the first pair and said inner roll of the second pair in the same direction but at reduced speed with respect to the outer roll of the second pair, a third gear train coupling the outer roll of the first pair to the inner roll of the first pair for simultaneous rotation in the same direction, a fourth gear train coupling the smooth roll to the inner roll of the first pair for simultaneous rotation in the same direction, and respective pressure rolls overlying and engaging the respective fluted rolls.
